UNITED STATES PATENT OFFICE.

RICHARD VARLEY, OF ENGLEWOOD, NEW JERSEY, ASSIGNOR TO THE AUTOcoil COMPANY,
A CORPORATION OF NEW JERSEY.

IGNITION SYSTEM FOR EXPLOSION-ENGINES.

No. 902,782.

Specification of Letters Patent.

Patented Nov. 3, 1908.

Application filed October 1, 1906. Serial No. 336,859.

To all whom it may concern:

Be it known that I, RICHARD VARLEY, a citizen of the United States, residing at Englewood, in the county of Bergen and State 5 of New Jersey, have invented certain new and useful Improvements in Ignition Systems for Explosion-Engines, of which the following is a full, clear, and exact description.

My invention relates to ignition apparatus 10 for explosion engines, and particularly a form of circuit breaker or timer for closing and opening the primary circuits of an induction coil or a plurality of induction coils discharging in the cylinders of the engine.

15 The principal object of the invention is to provide for making the duration of the spark cascade in the various cylinders constant, regardless of varying speeds of the engine. In other words, the object is to have the duration 20 of the primary circuit closure, measured in angular movement of the half time shaft, variable as the speed of the engine varies, so that the dwell or absolute duration of the primary circuit closure in units of time is constant, or having any predetermined relation.

25 A further object of the invention is to provide for automatically opening the primary circuits whenever the engine stops so as to insure against running down and injuring the 30 batteries.

35 A still further object of the invention is to improve and simplify the mechanical features of construction, and to render the mechanism very compact, efficient and easy of adjustment.

With these objects in view, the invention consists in the features of construction hereinafter set forth and claimed.

In the drawings: Figure 1 is a sectional 40 view showing a timing apparatus embodying the principles of my invention; Fig. 2 is a section on the line II—II of Fig. 1; Fig. 3 is a section on the line III—III of Fig. 1; Fig. 4 is a section on the line IV—IV of Fig. 1; Fig. 45 5 is a detail view of part of the revolving element looking upward from about the line II—II of Fig. 1; Figs. 6 and 7 are detail sectional views of certain contacting rollers employed; Fig. 8 is a top plan view of the apparatus; Fig. 9 is a diagram illustrating the circuit connections; Fig. 10 is a detail sectional view showing a locking means for fixing the angular adjustment of parts of the casing.

55 By the present invention I provide centrif-

ugal means which are capable of keeping the duration of the primary ignition absolutely constant if desired, or variable in any exact predetermined relation to the speed of the engine. I further secure these objects by an 60 apparatus which opens the primary circuits at contact points through a cam impelled lever, thereby retaining all the advantages of this type of circuit opener which is found to be very satisfactory in practice. 65

Referring to the drawings in which like parts are designated by the same reference sign, 1 indicates a frame or casing, preferably a metallic shell or drum angularly adjustable on a support 2, by means of the 70 slots 3 in a flange 4, through which project the studs 5. 6 and 7 are respectively springs and washers for holding the parts in proper relation. These features may be of the ordinary or any desired construction. 75

The half time shaft is shown at 8, revolvable in the support 2, concentrically within the casing 1. This shaft carries separate means for closing and opening the primary circuit, and also means for varying the angular relation of the circuit closing and circuit opening action as the speed of the engine varies. 80

The primary circuit closing devices are carried by a frame 9, fixed to rotate with the 85 shaft 8, and having a pair of parallel flanges 10, 11. The frame 9 is fixed in any desired angular relation to the shaft 8 by intermeshing crowns 12, 12', respectively on the flange 11 and on a flange 13 which is permanently fixed to the half time shaft. It is evident that these crowns may be positioned in any desired angular relation with one another. 90

Between the flanges 10 and 11 extend a 95 plurality of vertical studs 14 and 15. The stud 14 carries a swinging finger 16, spring impelled outward by a spring 17, and having a roller 18, at its extremity. This roller constitutes the primary circuit closing device. 100 The studs 15 also carry fingers 19, with rollers 20, at their extremities. These fingers are normally spring impelled inward by springs 21. The disposition of the various rollers is such that rollers 20 move in an entirely 105 different horizontal plane from the plane of the roller 18, as shown in Fig. 1. The rollers 20 constitute devices for opening the primary circuit automatically whenever the engine is at rest. 110

Within the casing 1 and arranged in horizontal zones about the various rollers are the metallic contacts therefor. The roller 18 has four segmental contacts 22, while the 5 two rollers 20 are capable of moving into contact with a single continuous metallic ring 23. The segments 22 and the ring 23 are insulated from the casing 1 in any convenient way, as, for example, by the insulating body 24. 10 Circuit connections are made with the various segments and with the ring 23, as will be later described. It is evident that the roller 18 is always impelled toward its contacting relation with its segments, but the 15 two rollers 20 are impelled inward and break contact with their ring 23 whenever the engine is at rest. When the engine is in motion, the rolls fly outward by centrifugal force and establish electric contact. In order 20 to obtain more compact disposition of the parts I make the flange 10 notched at 25 (Fig. 5), so as to provide spaces to receive the roller 18 and the fingers 19.

Upon the upper face of the flange 10 I 25 mount a centrifugal mechanism forming part of my invention and adapted to control the duration of the primary circuit closure. This centrifugal mechanism forms part of the same single rotating mass with the circuit 30 control 18 and the cam 31, together with the shaft 8. For this purpose two studs 26 are shown projecting upward from the flange 10 and each having thereon a pivoted arm 27 which is weighted at its outer end.

35 28 indicates springs secured to the arms 27, and to points on the flange 10, so as to normally impel the arms inward. Each of the arms has a stud 29, and these studs project into slotted extensions 30 of a cam sleeve 31, 40 loose on the half time shaft. The cam sleeve 31 is exteriorly shaped so as to move the primary circuit breaking lever. The slots, designated 30', in the extensions 30 are curved in such a way that the cam sleeve is displaced 45 angularly with relation to the half time shaft an amount which is exactly proportional to the speed of the half time shaft. This result may be attained by experiment, or it is possible to calculate the form of the slots mathematically. In case it were desired to have 50 another relation of the primary dwell than a constant one for all engine speeds, this also could be exactly attained by suitably forming the slot 30'. The primary circuit breaking lever is contained in an upper chamber of the casing. This may be attained in practice by a cylindrical shell 32 threaded on to the casing 1 at 33. 34 denotes a diaphragm of this shell formed of insulating material, 55 and 35 indicates a cover removably placed upon the shell to close the same.

The primary circuit breaking lever is designated at 36, pivoted on a stud 37, forming part of the shell 32.

65 38 indicates a roller carried by the lever 36

and adapted to contact with the cam projections 31'. The lever is normally impelled toward the cam by compression spring 39. In the path of the lever 36 and preferably impinged by an insulated button 40 at the 70 extremity thereof, is a resilient blade spring 41, mounted on a block 42, which is insulated from the casing by being supported on the insulating plate 34.

43 denotes a screw adjustable in proximity 75 to the blade 41, and both the blade, and the screw may be tipped with platinum contacts if desired. The screw 43 is grounded on the frame in use. It is evident that the blade 41 is grounded whenever the lever 36 enters a 80 depression of the cam, but this ground connection is broken whenever the projections of the cam impel the lever outward.

The operation will be understood from the foregoing description and from a consideration of Fig. 9, in which a practical arrangement of the electric circuits is shown. In this figure a plurality of induction coils have their primary circuits N' , N^2 , N^3 and N^4 (which may or may not be provided with vibrators 90 v) all connected to the various segments 22. The other terminals of the primary windings run to a common connection l' of battery B. The mechanism is designed to ground the other terminal l^2 of the battery, and the segments 22 simultaneously, so that the circuit of one or another of the primary coils N' , N^2 , N^3 or N^4 , will be completed. The mechanism also changes the relation of the time when the two grounding devices act, so that the 100 period of the primary dwell is varied. Tracing the circuit for primary N^4 , for example, current passes from battery B, through wire l' , primary N^4 , corresponding segment 22, and roller 18. From roller 18 current travels through the frame and metallic parts to the screw 43, which is grounded in use, as above stated. As long as the blade 41 is in contact with this screw, the circuit is completed through the wire l^2 to battery B. This causes the ordinary discharge in the secondary S^4 , one terminal of which is connected to a spark plug (not shown), the other secondary terminal being grounded as usual. The angular relation of the roller 18 and the cam 110 31 is such that the blade 41 is impelled away from the screw 43 before roller 18 leaves segment 22. Accordingly the primary circuit is positively broken between non-oxidizing contacts by a cam impelled lever in the most 115 efficient manner. This characteristic of my invention I regard as a very important one, and is perhaps the most distinguishing feature thereof.

In the above description I have referred 125 to the screw 43 being grounded. This is normally the case, but means are provided for breaking such ground connection whenever the engine stops. For this purpose the screw is connected by a wire n with the ring 23, 130

which contacts with the rollers 20 as long as the engine is moving and therefore makes the ground connection. When the engine stops, however, the rollers leave the ring by virtue of their springs 21, so that the screw 43 is no longer grounded, and there is no possibility of completing the primary circuits except by special or additional circuits. Such special circuits are made by the wires *o* connected to the ring 23, and having push buttons *r* by which such connections can be grounded on the frame of the machine at any desired point. In a motor car the ground connection would be made near the radiator in front, and also at the driver's seat. It is merely necessary to press any one of these buttons when cranking the engine. As soon as the engine commences to rotate, the ground connection is made by the rollers 20, so that closure by the buttons *r* is no longer required.

An incidental feature of the invention relates to the means for adjusting the parts and particularly the circuit breaking lever 36 with respect to the segments 22. As has been already stated, the primary circuit is completed only when the roller 18 and the blade 41 are simultaneously contacting with a segment 22 and screw 43 respectively. In practice it is desirable to have the angular relation of the segments 22 and the lever 36 adjustable, so that the primary dwell may be made of any desired duration. It is evident that if the shell or upper casing 32 is rotated in a left-hand or anti-clockwise direction with respect to the casing 1, that the primary dwell is shortened because under these circumstances, the blade 41 is impelled away from its contact when the roller 18 is at an earlier point on said segment 22. Thus the duration of the primary dwell is fixed in advance by the above mentioned adjustment, and maintained constant by the centrifugal device herein described, and adjusted with respect to the engine spark by the usual timing lever, which rotates the entire casing 1 in the usual way, and need not be described. The practical means for fixing the adjustment which I have employed comprises a plunger 45 guided in a recess 46 in the casing 1, and spring impelled upward by a spring 47. 48 indicates cavities on a flange 49 of the upper casing or shell 32. When the upper casing has been screwed down to the required extent on the casing 1, its angular position is fixed by the plunger 45 entering any desired one of the cavities 48.

If at any time it is found that the throw of the usual timing lever is not satisfactory, this trouble can be corrected by displacing the flange 11 on the flange 13 through the intermeshing teeth 12, 12'. This is sometimes desirable because the usual timing lever has a fixed arc or throw on the steering wheel, and if by reason of wear, or imperfect link connections, this fixed arc of throw does not corre-

spond to the requisite arc of throw in controlling the engine, it is important that the adjustment be corrected in the manner above stated.

What I claim, is:—

1. In an ignition system for explosion engines, rotatable means forming part of a single mass for closing the primary circuit at one point and for opening it at another point, and centrifugally operated means forming part of the same single rotating mass with said rotatable means, for varying the interval between such closing and opening with relation to the speed of the engine. 70

2. In an ignition system for explosion engines, rotatable means forming part of a single mass for closing the primary circuit, a cam for opening such circuit, and means forming part of the same rotating mass with said cam for angularly adjusting the same, 80 whereby the duration of the primary current with relation to the engine speed is varied.

3. In an ignition system for explosion engines, rotatable means forming part of a single mass for closing the primary circuit, a pair of contact points, and means controlled by the speed of the engine and rotat- 90 ing co-axially and synchronously with said rotatable means and being made a part of the same rotating mass, for breaking said circuit at such contact points at a varying interval after such circuit closure with respect to the speed of the engine. 95

4. In an ignition system for explosion engines, rotatable means forming part of a single mass for closing the primary circuit, cam operated means for opening the primary circuit, and a centrifugally operated device revolving co-axially and synchronously 100 with said cam operated means and being made a part of the same rotating mass, for varying the relative positions of said means. 105

5. In an ignition system for explosion engines, a shaft rotating commensurately with the engine, a sleeve on said shaft guided to have an independent angular movement, a cam on said sleeve, centrifugal devices for imparting an angular movement to said sleeve, means in the path of said cam for 110 opening the primary circuit, and additional means for closing the primary circuit at an unvarying time in the engine cycle. 115

6. In an ignition system for explosion engines, a half time shaft, means on said shaft 120 for periodically closing the primary circuit, a pair of contact points also included in said circuit, a cam on said shaft for separating said contact points, and means angularly movable with said cam for adjusting the 125 angular relation of said cam and said circuit closing means.

7. In an ignition system for explosion engines, a shaft having a circuit closing arm thereon, segments concentric with said shaft 130

and lying in the path of said arm, a primary circuit breaking lever, a cam on said shaft for impelling said lever into circuit breaking relation, and means for angularly adjusting said cam and arm with respect to one another.

8. In an ignition system for explosion engines, a casing having insulated segments therein, a shaft within said casing having an arm to engage said segments, a shell on said casing and angularly adjustable with respect thereto, a circuit breaking lever supported by said shell, and a cam on said shaft to impel said lever into circuit breaking relation.

9. In an ignition system for explosion engines, a casing, a shell threaded thereto, said shell having cavities therein, and a plunger on said casing spring impelled into engagement with said cavities.

10. In an ignition system for explosion engines, a circuit breaking lever, a cam acting on said lever and having extensions with curved slots therein, and a pair of weighted

arms revoluble co-axially with said cam and 25 having studs engaging said slots.

11. In an ignition system for explosion engines, a shaft, a cam sleeve loosely mounted thereon, said cam sleeve having lateral extensions with curved slots therein, a pair of 30 weighted arms having studs engaging said slots, springs for normally impelling said arms inward, and means for revolving the said arms in an orbit co-axial with said shaft.

12. In an ignition system for explosion engines, driving means, a cam sleeve having lateral slotted extensions and weighted arms engaging said slotted extensions to displace the cam sleeve rotarily with respect to its 40 driving means.

In witness whereof, I subscribe my signature, in the presence of two witnesses.

RICHARD VARLEY.
